NEUTRALIZED SYSTEM

Klaas Posthumus, Eindhoven, Netherlands, assignor, by mesne assignments, to Radio Corporation of America, New York, N. Y., a corporation of Delaware

Application August 10, 1938, Serial No. 224,063
In Germany September 10, 1937

8 Claims. (Cl. 179—171)

This invention relates to a high frequency amplifier comprising neutralizing condensers for compensating the capacity between anode and grid of the discharge tubes available in the arrangement.

It is sought to design the arrangement in such manner that the neutralization is independent of the frequency, since otherwise there would be a risk of one or more spontaneously generated oscillations occurring in addition to the oscillations to be amplified. This result could always be obtained in arrangements, wherein the conductors connecting one or more electrodes to connecting points outside the tube have an inductance which may be neglected for the oscillations to be amplified.

In the case of short wave amplification, however, the obtention of sufficient stability involves serious difficulties, since for these short waves the inductance of the same conductors is not negligible. This applies more particularly for amplification of large quantities of energy for which water-cooled tubes are usually employed since it is necessary, in view of the size of the tubes, to increase the length of the different conductors.

According to the present invention the desired effect is obtained by tuning the conductors, by which one or more electrodes are connected to connecting points outside the tube and whose inductance is not negligible for the oscillations to be amplified, to the frequency of the oscillations to be amplified, and by inserting a damping resistance in the conductor through which the input impedance and the neutralizing condenser(s) are connected to the grid, said damping resistance being shunted by a short circuit for the oscillations to be amplified. This short-circuit preferably consists of the series connection of an inductance and a capacity which is tuned to the frequency of the oscillations to be amplified.

The invention will be more clearly understood by reference to the accompanying drawings.

Figure 1 shows the diagram of connections of a well known neutralized amplifier comprising two push-pull connected discharge tubes.

Figure 2 is the substitution diagram of the arrangement shown in Figure 1.

Figure 3 shows the same diagram of connections but embodies the improvement according to the invention.

Figure 4 illustrates an improvement of the arrangement shown in Figure 3, and

Figure 5 represents an arrangement comprising an amplifying tube, according to the invention.

In Figure 1, the cathode grid and anode of two push-pull connected discharge tubes are designated by K₁, G₁, A₁ and K₂, G₂, A₂ respectively. Between the grids G₁ and G₂ is connected an oscillatory circuit 3 to which are supplied the oscillations to be amplified and which is tuned to the frequency of the oscillations to be amplified. A circuit 4, which is also tuned to the frequency of the oscillations to be amplified, is connected between the anodes A₁ and A₂ of the tubes 1 and 2. The anodes A₁ and A₂ are connected to the grids G₂ and G₁ respectively through neutralizing condensers designated by C₁ and C₂. The cathodes K₁ and K₂ are interconnected through a conductor 5. For the sake of clearness the required feed sources are not represented in the drawings.

When using water cooled discharge tubes in the arrangement shown in Figure 1 the plates of the neutralizing condensers connected to the anode can be provided in the immediate vicinity of the anode, so that the conductors connecting the anodes A₁ and A₂ to the connecting points O₁ and O₂ may be made very short so as to have a negligible inductance to the oscillations to be amplified. However, the conductors 1 connecting the grids G₁ and G₂ to the connecting points P₁ and P₂ respectively, as well as the cathode connecting leads 5 usually have such a length that the inductances of these leads are not negligible in amplifying ultra high frequency oscillations.

Figure 2 shows the substitution diagram of the arrangement represented in Figure 1, wherein the condensers between the point G₁, K₁, A₁ and G₂, K₂, A₂ respectively represent the inter-electrode capacities of the tubes 1 and 2 respectively, whereas the inductances 5, 7, 8 represent the connecting leads between the two cathodes K₁, K₂ between the grid G₁ and the connecting point P₁ and between the grid 2 and the connecting point P₂.

When the reactances of the inductances 5, 7 and 8 have a negligibly small value the arrangement shown in Figure 2 constitutes a Wheatstone bridge so that with a suitable size of the condensers C₁ and C₂ a tension set up between the points A₁ and A₂ cannot cause a tension between the points G₁, K₁ and G₂, K₂ respectively. When amplifying frequencies at which the reactances of the conductors 7 and 8 are not negligible the equilibrium of the bridge is disturbed so that the desired neutralization is not ensured. Moreover, the conductor 5 is traversed by a current which, at these high frequencies, brings a considerable potential difference between the points K₁ and K₂.

thus disturbing also the equilibrium of the bridge arrangement.

As regards the frequency of the oscillations to be amplified the detrimental influence of the inductance of the conductors 5, 7 and 8 can be obviated by tuning these conductors to the said frequency. This is effected by inserting in each conductor a condenser whose reactance to the frequency of the oscillations to be amplified is equal and opposite to the inductance of the conductors. In this case the total reactance of each of the conductors 5, 7 and 8 will be zero for the frequency of the oscillations to be amplified so that complete neutralization can be achieved for this frequency. For all other frequencies, however, there is no equilibrium in the bridge arrangement, so that additional measures have to be taken for avoiding the spontaneous generation of oscillations having other frequencies, more particularly higher frequencies. According to 20 the invention this measure consists in inserting a damping resistance in the conductors 7 and 8 through which the input impedance and the neutralizing condensers are connected to the grids, said damping resistance being bridged by a short-circuit for the oscillations to be amplified.

Figure 3 shows a circuit arrangement according to the invention which substantially corresponds to the arrangement shown in Figure 1, but which embodies the improvements constituting the object of the invention. The conductor 7 between G_1 and P_1 and conductor 8 between G_2 and P_2 include a series condenser 17 by means of which these conductors are tuned to the frequency of the oscillations to be amplified. Furthermore, these conductors comprise a damping resistance 19 which is bridged by a short circuit for the oscillations to be amplified. This short circuit consists of the series connection of an inductance 20 and a capacity 21 which are together tuned to the frequency of the oscillations to be amplified. Furthermore, the connecting line 5 between K_1 and K_2 comprises condensers 15 and 16 by means of which each of the two parts of this connecting line on either side of the connecting point 14 of the circuits 3 and 4 are tuned to the frequency of the oscillations to be amplified.

Of course, complete suppression of any reaction, such as is ensured by the arrangement according to the invention, causes a decrease in amplitude of the oscillations occurring in the circuit 4. To provide that the amplification is as strong as possible it is consequently desirable in the arrangement according to the invention to avoid all influences that may involve a further decrease of the output voltage. One of these detrimental influences is the mutual induction between the conductors that connect the electrodes of the amplifying tubes to connecting points outside the tube. In fact, this mutual induction causes a negative back coupling between the circuits 4 and 3 thus causing a decrease of the output voltage.

According to a further feature of the invention this detrimental influence is entirely or partly removed by providing that the inductance, which forms part of the circuit constituting for the frequency to be amplified a short circuit of the damping resistance included in the grid circuit, is inductively coupled to the cathode lead.

Figure 4 shows one form of construction of an amplifying circuit according to the invention, wherein this arrangement is used. Each of the inductances 20 is coupled to an inductance 22

included in the cathode lead of the corresponding tube. Consequently, the coil 20 in the grid supply conductor 7 of the tube 1 is coupled to a coil 22 inserted in the part of the conductor 5 between the point 14 and the cathode K_1 , whereas the coil 20 in the grid supply conductor 8 of the tube 2 is coupled to a coil 22 inserted in the part of the conductor 5 between the point 14 and the cathode K_2 . The maximum output energy is obtained by proportioning the coupling so that the coupling between the electrode supply conductors inside the tube is completely removed.

Figure 5 shows an amplifying arrangement according to the invention which differs from the arrangement represented in Figure 4 in that there is provided only a single amplifying tube 1. The output circuit 4 is connected between the anode and the cathode of the tube 1 and the grid is connected to one end of the input circuit 3 whose other end is connected through a neutralizing condenser C_1 to the anode. A point on the input circuit 3 between the ends is connected to a point 14 of the cathode conductor 5. In this arrangement the electrode-supply conductors 5, 11 and 17 are tuned, when necessary, by means of condensers 15, 18 and 17 to the frequency of the oscillations to be amplified, and the grid conductor 7 comprises a damping resistance 19 which is bridged by the series connection of a coil 20 and a condenser 21 tuned to the frequency of the oscillations to be amplified. The coil 20 is inductively coupled to a coil 22 inserted in the cathode conductor 5.

The coils 20 and 22 shown in Figures 3, 4, and 5 need only have a small self induction and will often consist only of a single turn.

I claim:

1. In an ultra-high frequency amplifying system, an electron discharge tube having an input electrode, a cathode and an output electrode, a high frequency input circuit, a high frequency output circuit, means series tuned to the frequency of said input circuit connecting said input circuit to said input electrode, a damping resistance in series with said means, means connecting said output circuit to said output electrode, neutralizing means coupling said input and output electrodes, and a circuit series tuned to the frequency of operation of said high frequency input circuit connecting said cathode to said high frequency circuits.

2. In an ultra high frequency amplifying system, an electron discharge tube having an input electrode, a cathode and an output electrode, a high frequency input circuit, a high frequency output circuit, means series tuned to the frequency of said input circuit connecting said input circuit to said input electrode, means connecting said output circuit to said output electrode, neutralizing means coupling said input and output electrodes, a circuit series tuned to the frequency of operation of said high frequency circuits connecting said cathode to said high frequency circuits and a coupling between said series tuned circuit and said means series tuned to the frequency of said input circuit.

3. In a neutralized amplifier comprising an electron discharge device having input and output electrodes including a cathode, high frequency input and output circuits connected with the input and output electrodes in said device respectively and a neutralizing circuit inter-connecting the said input and output electrodes, means for stabilizing said amplifier comprising means for tuning out the inductive reactance in

a connection between said circuits and an electrode of said device, means for reducing voltages of frequencies different than the frequency of operation of said circuits including a damping resistance in said connection and a circuit series tuned to the frequency of operation of said input and output circuits connected in shunt to said damping resistance.

4. A system as recited in claim 3 wherein said series tuned circuit in shunt to said damping resistance comprises a condenser and inductance.

5. A system as recited in claim 3 wherein the cathode of said device is connected to said circuits by a circuit series tuned to the frequency of operation of said circuit and wherein said last named series tuned circuit is coupled to the circuit in shunt to said damping resistance.

6. In a high frequency amplifier, an electron discharge device having input and output electrodes including a cathode, high frequency input and output circuits connected with the input and output electrodes in said device respectively, a neutralizing circuit connected between said input and output electrodes, a portion of said neutralizing circuit connection being common to the connection of said input circuit to said input electrodes, means for stabilizing the operation of said amplifier comprising capacitive means in said common portion of said connections for tuning out the inductive reactance in said connections, means for reducing voltages of all frequencies different than the frequency of operation of said input and output circuits including a damping resistance in said common portion of said connections and a circuit series tuned to the

frequency of operation of said input and output circuits connected in shunt to said damping resistance.

7. A system as recited in claim 6 wherein said series tuned circuit in shunt to said damping resistance comprises a condenser and inductance.

8. In a high frequency amplifier, an electron discharge device having an input electrode, an output electrode, and a cathode, high frequency input and output circuits connected with the input and output electrodes in said device respectively, a circuit series tuned to the frequency of operation of said input and output circuits in a connection between said cathode and said input and output circuits, a neutralizing circuit connected between said input and output electrodes, a portion of said neutralizing circuit connection being common to the connection of said input circuit to said input electrode, means for stabilizing the operation of said amplifier comprising capacitive means in said common portion of said connections for tuning out the inductive reactance in said connections, means for reducing voltages of all frequencies different than the frequency of operation of said input and output circuits including a damping resistance in said common portion of said connections and a circuit series tuned to the frequency of operation of said input and output circuits connected in shunt to said damping resistance, and a coupling between said series tuned circuit in shunt to said damping resistance, and said series tuned circuit in said connection between the cathode of said tube and said input and output circuits.
